UNITED STATES PATENT OFFICE.

WEEDEN B. UNDERWOOD, OF ERIE, PENNSYLVANIA, ASSIGNOR TO AMERICAN STERILIZER COMPANY, OF ERIE, PENNSYLVANIA, A CORPORATION OF PENNSYLVANIA.

PROCESS OF OBTAINING STERILIZED AND DISTILLED WATER.

1,183,142.

Specification of Letters Patent.

Patented May 16, 1916.

Application filed December 26, 1914. Serial No. 879,061.

To all whom it may concern:

Be it known that I, WEEDEN B. UNDERWOOD, a citizen of the United States, residing at Erie, in the county of Erie and State 5 of Pennsylvania, have invented new and useful Improvements in the Process of Obtaining Sterilized and Distilled Water, of which the following is a specification.

This invention relates to the process of 10 obtaining sterilized and distilled water and consists in certain improvements therein as will be hereinafter fully described and pointed out in the claims.

The object of the invention is to supply 15 sterilized and distilled water in such quantities as are ordinarily necessary in connection with water sterilizers. For some purposes distilled water is necessary and not only is it necessary that the water be distilled so as to take out such impurities as may be taken out by distillation but it is also desirable that the water from which the distilled water is taken should be sterilized.

It has been common to sterilize water for 20 hospital and general uses and this is ordinarily done by bringing the water to a temperature considerably above the boiling point, as for instance, 250° F. and maintaining the water at this temperature some 25 time varying somewhat according to the judgment of the operator but ordinarily from twenty to thirty minutes. This temperature involves a pressure of something like fifteen pounds. Before the sterilized 30 water so subjected to this temperature can be utilized, the temperature must be reduced to the boiling point so that the water so drawn from the supply will not be dissipated nor flash into steam when released.

40 In the present invention this added heat is utilized by permitting the steam to be evolved through the action of this heat by the release of pressure. The steam so evolved is collected, condensed and the distilled water collected from the condensation maintaining a sterilized condition with relation to the steam condensation and the collection of the distilled water. Not only is distilled water provided but it is provided from 45 sterilized water and the excess of heat ordinarily used in sterilizing water is utilized so that distilled water is provided as an incident to the sterilizing process without additional heat.

55 In carrying out my invention I have illus-

trated an apparatus suitable for the purpose in the accompanying drawings wherein the sterilizing tanks 1—1 are of the usual form. They are carried by the frame 2. Each of these tanks has the usual fittings, that is to say, the filtered air vent 4 so that water may be drawn from the tank, a safety valve 5, and air valve 6 permitting the escape of air. Water is delivered to the tanks 1 through the pipe 7. Preferably the water is filtered (filter not shown). Each tank is supplied with a blow-off pipe 8. The coil 9 is arranged in one of the tanks which is ordinarily designed to hold hot water and the coil 10 in the other of said tanks ordinarily designed 60 to hold cold water. Steam from any suitable supply is delivered through the coil 9 and at a temperature and pressure to raise the temperature of the water in the tank 1 in which the coil 9 is located to a temperature above the boiling point and to maintain it at this temperature a sufficient time to sterilize it.

The condenser 11 has a condensing coil 13 which is connected by way of the pipe 12 with the sterilizing chamber. The pipe 12 is controlled by a valve 12^a. The coil 13 is connected by a pipe 14 with the distilled water reservoir 15. Water is circulated through the condenser 11 by means of the pipes 16 and 17 in the usual manner. The distilled water reservoir 15 has the usual fittings, water gage 18, draw-off valve 19, air filtered vent 20, safety valve 21 and automatically operated valve 22 for allowing the escape of air.

In carrying out my process with this apparatus water is delivered to the sterilizing chamber or reservoir 1, steam is turned into the coil 9 at a temperature to raise the temperature of the water in the reservoir 1 to above the boiling point and to maintain it at this temperature a sufficient time to sterilize the water. It will be understood that at this high temperature there is pressure as the usual sterilizing temperature of 250° F. involves a pressure of fifteen pounds. After the water is sufficiently sterilized, the valve 12^a is opened thus releasing the pressure in the reservoir 1; immediately steam is evolved incident to this release of pressure and passes to the condenser where the water is condensed and then passes by the pipe 15 to the distilled water reservoir. All these parts may be 65 70 75 80 85 90 95 100 105 110

thoroughly sterilized by simply passing steam through the different reservoirs prior to the sterilizing operation.

In this process, therefore, sterilized distilled water is obtained and in the ordinary hospital practice is obtained without additional cost in that the heat ordinarily lost with relation to the sterilizing operation is utilized for furnishing the steam from which the distilled water is obtained, this steam being as above described from sterilized water.

What I claim as new is:—

1. The process of obtaining sterilized and distilled water which consists in heating the water above the boiling point and maintaining it at this temperature to sterilize the water, then releasing the pressure, storing the sterile water thus obtained at a temperature for use, collecting and condensing the steam evolved incident to the rediced

pressure and high temperature and collecting the water condensed.

2. The process of obtaining sterilized and distilled water which consists in heating the water above the boiling point and maintaining it at this temperature to sterilize the water, then releasing the pressure, storing the sterile water thus obtained at a temperature for use, collecting and condensing the steam evolved incident to the reduced pressure and high temperature and collecting the water condensed, maintaining the sterile conditions as the steam is collected, condensed and the distilled water collected. 35

In testimony whereof I have heretinto set my hand in the presence of two subscribing witnesses.

WEEDEN B. UNDERWOOD.
